UNITED STATES PATENT OFFICE.

JOHN S. HEALY, OF BROOKLYN, NEW YORK.

GAS-BURNING APPLIANCE.

1,385,545.

Specification of Letters Patent. Patented July 26, 1921.

Application filed June 25, 1920. Serial No. 391,623.

To all whom it may concern:

Be it known that I, JOHN S. HEALY, a citizen of the United States, residing at Brooklyn, in the county of Kings and State 5 of New York, have invented a new and useful Gas-Burning Appliance, of which the following is a specification.

This invention relates to the mixing of gas and air preparatory to combustion, and 10 the principal objects thereof are to provide as near perfect combustion as possible by the proper mixing; to effect a saving in the gas required to produce a given amount of heat; to provide a system which will be 15 very simple in construction and contain few parts and will apply the flame direct to the article to be heated without over-heating any particular region, thus giving a uniform and safe application of heat; also to provide 20 a construction of mixer that will work with any kind of burner, and thus be universally adaptable; and more specifically to provide a mixing device occupying very little room and suitable for use anywhere 25 in which air under relatively low pressure can be employed for bringing in atmospheric air and thoroughly mixing it with the gas which it then conveys directly to the burner. Further objects and advantages 30 of the invention will appear herein.

Reference is to be had to the accompanying drawings in which—

Figure 1 is a central sectional view of a stereotype melting furnace with a preferred 35 embodiment of this invention applied thereto; and

Fig. 2 is a sectional view on the line 2—2 of Fig. 1.

I have shown the invention as applied to 40 the melting pot of a stereotype melting furnace which, as ordinarily constructed, will hold a large amount of metal, perhaps 20,000 lbs. This must all be pumped out in sixty minutes at a temperature of 650 degrees. 45 This invention has been successfully used with such a furnace which furnishes obviously a severe test to its value.

The melting pot 10 of the stereotype melting furnace is shown as mounted in the 50 usual way, and I have not shown its upper connections. Under it is placed a gas burner 11 shown as of the annular type having a flat ring directly under the pot pierced by numerous jet openings arranged 55 in a circle. This burner is shown as having a space 12 at the bottom of cup-shape com-

municating through an opening 13 with a passage 14, preferably in the form of a pipe, for the inlet of the combustible mixture. This pipe 14 leads directly from a small 60 chamber 15. This chamber is supplied with gas through a pipe 16 in any ordinary way, the pipe entering at one side.

Projecting into this chamber 15 past the opening 17 for the admission of the gas is 65 a nozzle 18. This nozzle has behind it an annular chamber 19 into which air is pumped through a pipe 20 under comparatively low pressure. I have found 6 lbs. pressure to be sufficient. A positive pressure 70 blower is employed to produce a large flow of air at about that pressure. The air is introduced through the pipe 20 as stated and has direct control over the admission of the free air which comes in concentrically in 75 the center of the nozzle. This nozzle has a uniform accurate action. I use no shutter or other adjustment of the free air pipe, so that it has free admission which is uniform under all conditions. By employing only a 80 low pressure I avoid the use of a compressor. The opening from the pipe 20 enters the annular chamber 19 at one side and at the rear of the nozzle 18. This nozzle and the chamber are both made annular from the fact that 85 a pipe 21 enters them centrally and passes concentrically all the way through them to the inner end of the nozzle. This pipe 21 extends in from the outside of the building for the purpose of conducting atmospheric 90 air into the mixing chamber 15.

It will be noted that the nozzle so-called, 18, is of reduced diameter with respect to the chamber 19 so as to form an annular jet of compressed air issuing out into the mixing chamber 15 and directly into the end of the pipe or passage 14. The mixing chamber surrounds the end of the pipe 21 and brings in the atmospheric air by induction. This reduces the pressure in the chamber 15 somewhat and sets up eddy currents of air therein which assist in taking up the gas from the opening 17 at the rear of this mixing chamber, assuring a complete mixture of the gas and air. The gas, coming 100 in on one side only under the lower pressure, apparently has the effect of spreading in both directions around the projecting nozzle 18 and thus somewhat modifies the annular current of air under a slightly 110 higher pressure which issues into the mixing chamber 15. This seems to add to the

effectiveness of the mixing operation and yet the mixing chamber is so small and the distance between the nozzle 18 and the end of the passage 14 so short that the ingredients pass directly to the latter and from there to the burners, requiring no further mixing operation and not having time to separate in any way before combustion takes place.

10 As the free air is piped to the T 22 in which the chambers 15 and 19 are located, as well as the nozzle 18, it passes into the gas in the mixing chamber and then to the burner. Once the parts are properly proportioned and adjusted this mixing device gives only one result, namely, perfect combustion.

15 It is to be noted also that this system involves the direct heating of the melting pot 10 or other device to be heated, and that the use of small burners or clusters of burners is entirely done away with, a burner being provided which will last indefinitely and not requiring frequent replacement.

20 25 It is to be noted that the air under pressure, the free air and the gas all meet at the same point, that is in the small mixing chamber 15, and the success of the device is undoubtedly due mainly to the proper combination of these three elements and the bringing of them together within this small area. This in fact is so small that it is hardly properly descriptive to call it a chamber. The mixing occurs at the point at which the 30 35 air issues from the nozzle 18.

40 45 Although I have illustrated and described only one form of the invention I am aware of the fact that modifications can be made therein by any person skilled in the art without departing from the scope of the invention as expressed in the claims. Therefore I do not wish to be limited to all the details of construction, or to the special form of burner herein shown and described, but 50 what I do claim is:—

1. In a gas burning appliance, the combination with a burner having a passage leading thereto and directly communicating therewith, of a mixing chamber connected

50 directly with and leading directly into said passage, a nozzle located concentrically at the intake end of said passage and in alignment therewith, means for directing air under pressure into the passage, said nozzle having centrally extending thereinto and terminating at its end a passage for atmospheric air, and means for introducing gas into said chamber at the rear of the end of said nozzle.

55 60 65 70 75 2. In a gas burning device, the combination of a pipe for conducting gas and air to a burner, of a pipe for admitting atmospheric air located centrally in alignment with the end of said pipe and spaced slightly therefrom, a chamber surrounding the end of said air pipe and forming an annular passage around it, means for introducing air under low pressure into said chamber to draw in the atmospheric air and force them both into the first named pipe, and means for introducing gas into said chamber at the rear of the end of said air pipe, whereby the gas will be mixed with the air at the point at which the gas issues from the annular passage.

75 80 85 90 95 3. In a gas burning appliance, the combination with a burner having a passage leading thereto and directly communicating therewith, of a mixing device connected directly with said passage and comprising a chamber, a pipe for admitting atmospheric air located centrally in alignment with said passage, a nozzle concentrically surrounding the discharge end of said pipe, an annular chamber connected with the nozzle, means for introducing air under low pressure into said annular chamber, the nozzle and pipe terminating substantially at the same point, and means for introducing gas into the first named chamber around said nozzle, whereby the pressure air draws in atmospheric air and both are discharged under reduced pressure through the first named chamber directly into said passage drawing in the gas with them and thoroughly mixing the same.

In testimony whereof I have hereunto affixed my signature.

JOHN S. HEALY.
